(57) **CLAIM**

Applicant claims the ornamental design for a liquid propane container for an ice fishing enclosure, as shown and described.

DESCRIPTION

FIG. 1 is a front perspective view of a liquid propane container for ice fishing enclosure, showing my new design in a closed position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, in an open position.

The broken line showing of propane containers in FIG. 8 is included for the purpose of illustrating environment of the article and forms no part of the claimed design.
